DESIGN FOR A COMB

Oswald B. Carson, Scarsdale, N. Y., assignor to American Hard Rubber Company, New York,
N. Y., a corporation of New York

Application May 16, 1935, Serial No. 56,864

Term of patent 14 years

To all whom it may concern:

Be it known that I, Oswald B. Carson, a citizen of the United States and a resident of Scarsdale, in the county of Westchester and State of New York, have invented a new, original, and ornamental Design for a Comb, of which the following is a specification, reference being had to the accompanying drawing, forming a part thereof and in which the figure is a side elevation of a comb embodying my new design, the reverse side of the comb being substantially of the same appearance as the side shown.

I claim:

The ornamental design for a comb, as shown and described.

OSWALD B. CARSON.
